UNITED STATES PATENT OFFICE.

JOHN C. McLAUGHLIN, OF JERSEY CITY, NEW JERSEY, ASSIGNEE TO UNDERWOOD TYPEWRITER COMPANY, OF NEW YORK, N. Y., A CORPORATION OF DELAWARE.

TYPE-WRITING MACHINE.

1,080,117.

Specification of Letters Patent.

Patented Dec. 2, 1913.

Application filed June 4, 1910. Serial No. 564,967.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to tabulating mechanisms for typewriting machines, wherein usually a carriage movable upon a frame, has one or more column stops to contact with key-operated stops on the frame, to arrest the carriage at different points in the printing line, corresponding with the printing positions of the first characters in different columns, the carriage being jumped from the printing point of the last character in one column to the printing point of the first 20 character in the next column.

One of the objects of this invention is to enable the column stops to be quickly and easily shifted by an operator, to accord with different columnar arrangements of forms or blank sheets, no special skill being required to adjust the mechanism or the stops. To this end, several rack bars, each having stops arranged thereon, are shiftably mounted on the carriage, so as to be severally 30 brought into effective position relatively to the key-controlled stops.

Another object is to simplify and improve the mechanism whereby the column stops are releasably secured to the rack on which they are adjustably mounted, which I accomplish by providing each rack with a rotatable key to releasably lock the stops against removal from the rack by entering recesses formed in the stops.

In the accompanying drawings, Figure 1 is a perspective view of the invention, broken away and in section. Fig. 2 is a rear view, showing its relation to the key-controlled stops. Fig. 3 is an end view of the invention, partly in section, applied to an Underwood writing machine. Fig. 4 is a detail side view of a column stop. Fig. 5 is a cross-section through one of the tabulating racks. Figs. 6 and 7 are sectional views 45 through one of the racks showing the stop locked thereto and ready for removal therefrom, respectively. Fig. 8 is a view of the

opposite end of the rack support from that shown in Fig. 3.

A carriage 1 is mounted for movement back and forth along the rail 1^a of the frame 2 of an Underwood writing machine, and is drawn in one direction by a spring 3, the carriage having a rack 25 in mesh with the pinion 26 of an escapement mechanism, 60 said rack having arms 27 pivoted at 28 to the carriage.

To jump the carriage across the machine in letter-spacing direction, one of several tabular keys 4, (Fig. 3), on the frame 2 is depressed to operate a key lever 4^a pivoted at 4^b, and which projects a stop 5 carried by a plunger 5^a (sliding in a guide casing 6), into the path of a column stop 7 on the carriage 1, the operation of the key also effecting the release of the carriage from the usual letter-space mechanism to allow the carriage to move freely across the frame, under the influence of the spring 3 until the stop 7 (mounted on a rack 8 connected with the carriage) contacts with the key-controlled stop 5 to arrest the carriage. The release of the carriage is effected through an arm 30 carried by a shaft 31 mounted on the casing 6, and shifted by a shoulder 32 on any plunger 5^a. The plunger rocks the arm 30 to vibrate a second arm 33 on said shaft, said second arm being connected by a link 34 with one end of a releasing lever 35 pivoted at 36 to the frame 2. The opposite end of said lever contacts with the rack 25 to disengage the latter and hold it out of mesh with its pinion.

The rack 25 is restored to mesh with its pinion by a spring 29, and said stop 5, plunger 5^a, key lever 4^a, and key 4, are returned to normal position by a spring 5^b, the plunger being recessed at 5^c to accommodate a bar 5^d which limits the throw of the stop.

The stops 7 are forked to embrace the rack 8, being adjustably seated between teeth 11 thereof. They are held against accidental displacement by a key rod 9, turning in a groove 10 (Fig. 5), extending longitudinally of and formed partly in the bar and partly in the teeth 11 thereof, the legs 12 of said stops being recessed, as at 13, to be complementary to the groove.

The key rod 9 is cut away longitudinally

to form a face 15, and by turning said rod axially, by its finger piece 14, the unreduced periphery of the bar enters the recesses in the stops 7 on the bar to lock them in place. 5 Further rotation of the rod will bring the flat face 15 thereof opposite the recesses 13 in the stops to enable the stops 7 to be withdrawn from the rack bar, (Fig. 7).

A collar 16 at one end of the locking key 10 and a screw 17 at the opposite end, prevent endwise movement of the key 9 in the tabulating rack bar 8.

It will be noticed that the inner edges of both legs of the reversible stops 7 are recessed, so that the key may cooperate with either leg.

To avoid the readjustment of the column stops 7 on the rack bar each time a different form is inserted in the machine, or whenever 20 a different arrangement of columns is desired, and thereby to economize time and labor as well as to decrease the liability of error in adjusting the stops on the bar, I provide the carriage with several tabulating bars 8, 8^a, 8^b, 8^c, each bar carrying a series of column stops 7, arranged therealong to correspond with a columnar arrangement different from the arrangements for which the column stops on the other bars are set. 25 Said tabulating bars 8, 8^a, 8^b, 8^c, are fixed in heads 18, 18, fast on a shaft or pindle 19, journaled in brackets 20 fastened to the carriage 1.

Turning the shaft or pindle 19 by a hand wheel 21, (preferably having numerals, as shown in Fig. 2, designating the respective tabulating bars 8, 8^a, 8^b, 8^c), will revolve the tabulating bars relatively to the key-controlled stops 5, until the desired bar is 30 brought to operative position, where it is releasably locked by a spring finger 22, which enters the recesses 23 in a locking disk 24 fast on the shaft or pindle 19.

It will be seen that only one kind of stops 45 7 needs to be used, and that the operation is simple, the operator merely adjusting the stops along a rack in the ordinary manner, and then locking them, and then rotating the rack to working position.

50 Variations may be resorted to within the scope of the invention, and portions of the improvements may be used without others.

Having thus described my invention, I claim:

55 1. The combination in a tabulating mechanism of a typewriting machine, of a tabulating rack bar, a bifurcated stop adjustably seated between any two adjacent teeth of the rack bar, said stop being recessed, a rotatable locking rod connected to the rack bar and of greater diameter in one direction than in a direction transverse thereto to releasably enter the recess in said stop to lock it against movement on the bar and a finger 60 piece for rotating said rod.

2. In a tabulator, the combination with a rack bar, of a bifurcated stop having legs straddling said bar and having a recess in one of said legs, and a rotatable locking rod carried by the rack bar and releasably entering said recess in the stop to lock the stop against movement on the bar. 70

3. In a tabulator, a stop-carrying rack bar, a bifurcated stop having legs straddling said bar and having a recess formed in one of said legs, and a rotatable locking rod extending along the rack bar to releasably enter the recess to lock the stop and bar against relative movement. 75

4. In a tabulating mechanism for typewriting machines, the combination of a stop-carrying toothed bar having a groove on its toothed side, a locking rod rotatable in said groove, and a bifurcated stop adjustably seated astride the bar and having a recess complementary to the groove, into which said rod may swing out of the way of said stop to permit its withdrawal. 80

5. In a tabulating mechanism for typewriting machines, the combination of a stop-carrying toothed bar having a groove, a locking rod rotatable in said groove, and a bifurcated stop astride the bar and having oppositely located recesses, either of which is complementary to the groove, to accommodate the lock rod to hold the stop against movement. 85

6. In a tabulator, the stop-carrying rack-bar and a stop slotted to straddle said bar and provided with a notch therein, in combination with a rotary catch straddled by said stop and adapted to enter and to leave said notch to lock said stop in place and to release the same. 90

7. In a tabulator, the stop-carrying rack-bar and a stop slotted to straddle said bar between teeth thereof and provided with a notch in an edge thereof, combined with a movable eccentric for co-action with said notched edge to lock said stop on said bar 105 said eccentric straddled by said stop. 110

8. In a tabulator, the combination with a fixed bar adapted to hold tabulator-stops against motion along but not against motion in one direction transverse to said bar, of a stop adjustable along said fixed bar, and a lock-bar pivoted to rock, parallel to said fixed bar, into and out of engagement with said stop, to lock the same against displacement or to release it so it may have motion in said one direction. 115

9. In a tabulator, the combination with a fixed bar adapted to hold tabulator-stops against motion along but not against motion in one direction transverse to said bar, of a stop adjustable along said fixed bar and provided with a notch in an edge thereof substantially parallel to said one direction, and a rock-bar parallel to said fixed bar and engaged with and disengaged from said 120 125 130

notch by rocking to lock said stop against and releasing it for motion in said one direction.

10. In a tabulator, the combination with 5 a fixed rack-bar, of a stop slotted to straddle said bar between teeth of said bar and the slot thereof widened at a point between the open and the closed ends thereof, and a rock bar parallel to said fixed bar and engaged with and disengaged from said widened part by rocking it to lock said stop on and release it for removal from said rack-bar.

11. In a tabulator, a rack bar and forked 15 stops straddling the same, the slots forming the forks being widened at points inside the open end thereon, combined with a rotary bar of different dimensions transversely thereof and adapted to co-act with said stops 20 at the widened parts of said slots to lock and unlock the stops.

12. The combination with a rack, of stops having forks whereby they are inserted in said rack, said forks having notches, and a 25 locking bar extending along said rack and straddled by the forks, and rotatable into said notches to lock the stops.

13. The combination with a tabulator, of 30 a rack bar arranged to hold a stop thereon in a plurality of spaces, of a locking member lying within said rack, and arranged to be moved to enter into a recess in said stop, to lock it to the rack bar.

14. The combination with a tabulator, of 35 a rack bar arranged to hold a stop thereon in a plurality of spaces, a segmental bar journaled to rotate within said rack bar, having its solid portion arranged to lie wholly within the solid portion of said rack 40 in its inoperative position, and rotatable to intercept one edge of a stop and to enter a cutaway portion in said stop to lock it to the rack bar.

15. The combination with a tabulator, of 45 a rack bar arranged to hold a stop thereon in a plurality of spaces, said stop entering its unbroken head between teeth in said rack bar, using said head to coöperate with the tabulator plungers and positioned on said 50 rack by legs straddling it, and a locking member movable into and out of engagement with said stop to lock it to said rack bar.

16. In a typewriting machine, the combination with a traveling carriage, of a rotatable shaft journaled thereon, heads on 55 said shaft, a plurality of rack bars fast to said heads, stops settable on said bars, a finger piece outside the heads for rotating said shaft to bring a stop on a rack bar to

effective position, a lock for holding a stop 60 to its bar, and a finger piece lying outside the heads for operating said lock.

17. In a typewriting machine, the combination with a carriage and a shaft journaled thereon, of disks on said shaft, tabulator 65 stop carrying bars connected to the disks, and locking members for the stops journaled in said disks.

18. In a typewriting machine, the combination with a shaft and a finger piece for 70 turning it, of rack bars connected to the shaft for revolution about its axis, locking members carried on said shaft for locking stops to the rack bars, and finger pieces for turning the locking members into and out 75 of locking position.

19. In a tabulator, the combination with 80 a rack bar, of a bifurcated stop to straddle the rack bar and having recesses at opposite sides of the rack bar, said stop being reversible on the rack bar, and a locking rod carried by the rack bar and entering one of said recesses in the stop to lock the stop against movement on the bar, said rod being movable to release the stop. 85

20. In a tabulator, the combination with 90 a key-controlled stop, of a tabulator rack, column stops adjustable along the rack, and a locking key carried by the rack and engaging the stops to hold them against movement, said key being movable into position to permit the stops to be moved in a direction perpendicular to the rack, and thereby removed from the rack. 95

21. In a tabulator, the combination with 95 a rack bar, of stops adjustable along the rack bar, said bar and stops being provided with openings located within the outline of the rack bar, and a rod extending through said openings and movable into and out of 100 position to lock the stops on the rack bar.

22. In a tabulator, the combination of a stop-supporting bar formed with an opening extending longitudinally thereof, and a locking rod extending through said opening 105 and movable into and out of position to lock the stops to said bar.

23. In a tabulator, the combination with 110 a stop-supporting bar, of stops mounted thereon and adjustable longitudinally thereof, said bar formed with a longitudinal opening, and a locking rod swiveled in said opening and rotatable into and out of position to lock the stops on the bar.

JOHN C. McLAUGHLIN.
